UNITED STATES PATENT OFFICE.

EDWIN ELMER FREDERICK, OF BELLEVUE, PENNSYLVANIA, ASSIGNOR TO THE FREDERICK-ELDER COMPANY, OF PITTSBURGH, PENNSYLVANIA, A CORPORATION OF PENNSYLVANIA.

GAS-CONTROLLING DEVICE FOR BURNERS.

1,010,247.

Specification of Letters Patent. Patented Nov. 28, 1911.

Application filed September 4, 1909. Serial No. 516,171.

To all whom it may concern:

Be it known that I, EDWIN ELMER FREDERICK, a citizen of the United States, residing at Bellevue, in the county of Allegheny and State of Pennsylvania, have invented a new and useful Gas-Controlling Device for Burners, of which the following is a specification.

This invention relates to a controlling device designed more especially for inverted mantle gas burners, whereby the flow of gas can be accurately regulated.

The principal object of the invention is the provision of a novel valve-operating means of comparatively simple and inexpensive construction, reliable and efficient in use, and adapted preferably, although not necessarily, for inverted gas mantle lamps.

Another object of the invention is to provide simple and effective means for preventing leakage of gas around the rotary shaft which is employed for adjusting the position of the needle valve, thereby overcoming one of the serious objections of gas controlling valves used in connection with inverted mantle lamps, wherein the intense heat to which the device is subjected renders the same leaky.

With these objects in view and others, as will appear as the description proceeds, the invention comprises the various novel features of construction and arrangement of parts which will be more fully described hereinafter and set forth with particularity in the claims appended hereto.

In the accompanying drawings, which illustrate one embodiment of the invention, Figure 1 is a vertical central section of a gas controlling device for burners. Fig. 2 is a horizontal section on line 2-2, Fig. 1. Fig. 3 is a vertical section taken at right angles to that of Fig. 1. Fig. 4 is a perspective view of the valve-adjusting device and associated parts shown in disassembled position.

Similar reference characters are employed to designate corresponding parts throughout the views.

Referring to the drawing, A designates the casing or body of the valve, which is a hollow cylindrical structure internally threaded at its upper end for connection with a gas supply pipe 1 and having its lower end provided with a small jet orifice

2 at which is provided a conical valve seat 55. The lower end of the body A is externally threaded at 4 for connection with the usual gas mixing tube of the burner. The body has a side opening 5 at a point intermediate its ends, in which is threaded a tubular member or sleeve 6 which forms a bearing for the operating shaft 7 of the needle valve. In the body A is slidably mounted a rectangular frame 8 that has at its lower end a conical needle valve 9 which coöperates with the seat 3 for regulating the flow of gas into the mixing tube of the burner. The frame 8 of the valve is disposed diametrically of the body A and has its side edges convex for permitting the internal smooth wall of the body to guide the frame 8 back and forth in the opening and closing movement of the valve. The frame 8 has a longitudinal opening 10, and along one wall of the opening are rack teeth 75 11. Meshing with these rack teeth is a pinion 12 on the inner end of the shaft 7. By this means, the rotation of the shaft will raise or lower the valve and hence regulate the supply of gas. 80

It is extremely important that leakage of gas around the shaft 7 be prevented, since any leakage impairs the efficiency of the burner. For this purpose, the tubular member 6 has its inner end counterbored to form 85 a chamber 13 for receiving a packing 14 of asbestos or the like which resists the extreme heat to which the parts are subjected. The shaft has a collar 15 against which the packing bears, and threaded in the chamber 90 13 is a gland 16 for compressing the packing so as to prevent leakage around the collar 15. As shown in Fig. 4, the inner end of the member 6 is internally and externally threaded for receiving the gland and for 95 screwing into the body A. The inner end of the chamber 13 forms a shoulder against which the collar 15 bears, and this collar co-operates with the handle 17 on the outer end of the shaft 7 for rotatably holding the shaft 100 in the tubular member. The valve is maintained in coöperative relation with its seat by reason of the teeth 11 meshing with the teeth of the pinion 12, and furthermore, the valve cannot turn in the body A because of 105 the intermeshing relation of the teeth. The valve body does not require guides since it will move back and forth with perfect free-

dom, and owing to the absence of guides, the flow of gas through the body A is not restricted or the pressure reduced, as is the case with those devices in which guides for 5 the valve are necessary. With this arrangement, the position of the valve can be accurately adjusted for controlling the flow of the gas to the burner tube, and at all times 10 leakage and waste of gas from the body is prevented.

From the foregoing description, taken in connection with the accompanying drawing, the advantages of the construction and of the method of operation will be readily apparent 15 to those skilled in the art to which the invention appertains, and while I have described the principle of operation of the invention, together with the device which I now consider to be the best embodiment 20 thereof, I desire to have it understood that the device shown is merely illustrative, and that such changes may be made when desired as are within the scope of the claims appended hereto.

Having thus described the invention, what I claim as new, and desire to secure by Letters Patent, is:—

1. In a gas controlling device for burners, a valve casing having a longitudinal bore 30 of even diameter and at one end formed with a terminal wall having a small central gas orifice, a tubular member entering the casing at one side thereof in a direction perpendicular to the longitudinal axis of the casing, a valve member within the casing comprising a frame having internal gear teeth thereon and a valve adapted to move into and out of closing relation to the gas orifice at the end of the bore of the casing, 35 an actuating member for the valve comprising a shaft extending through the tubular member and having a pinion within the casing adapted to engage the gear teeth on the valve frame, and a packing gland for the 40 shaft entering the tubular member at the end within the valve casing and adapted to confine packing within said tubular mem-

ber, the packing gland and tubular member constituting the sole support for the shaft.

2. In a fluid controlling device, a suitable 50 casing, a valve therein, and a valve operating device comprising a tubular member having one end entering the casing, a shaft mounted in said tubular member and provided exterior to the casing with manipulating means and interior to the casing with valve operating means, said shaft having a collar thereon within the tubular member, said tubular member being interiorly enlarged for the reception of the collar and 60 threaded at the end within the casing, and a packing gland traversed by the shaft and entering the threaded end of the tubular member within the casing, the said packing gland being adapted to confine packing 65 about the shaft against the collar on said shaft.

3. A fluid controlling device, comprising a suitable casing, a valve comprising a closed frame having gear teeth along the inner 70 wall of one side of the frame, the said frame being adapted to slide in the casing, and manipulating means for the valve comprising a shaft, a manipulating member secured to one end of the shaft, an elongated 75 pinion at the other end of the shaft and adapted to engage the gear teeth on the valve frame, a tubular member carrying the shaft and entering the casing, and a packing gland surrounding the shaft within the casing and adapted to enter the end of the tubular member within the casing to confine packing about the shaft, the said shaft having a collar thereon within the tubular member against which collar packing confined 80 by the gland engages.

In testimony, that I claim the foregoing as my own, I have hereto affixed my signature in the presence of two witnesses.

EDWIN ELMER FREDERICK.
